UNITED STATES PATENT OFFICE.

MERLE P. CHARLIN, OF WHITE PLAINS, NEW YORK, ASSIGNEE TO WESTERN ELECTRIC COMPANY, INCORPORATED, OF NEW YORK, N. Y., A CORPORATION OF NEW YORK.

PRINTING TELEGRAPHY.

Application filed November 16, 1920. Serial No. 424,372.

To all whom it may concern:

Be it known that I, MERLE P. CHARLIN, a citizen of the United States, residing at White Plains, in the county of Westchester, State of New York, have invented certain new and useful Improvements in Printing Telegraphy, of which the following is a full, clear, concise, and exact description.

This invention relates to printing telegraphy and particularly to printing telegraph receiving apparatus including distributing, selecting, translating and recording mechanisms.

An object of this invention is to provide a receiving instrument of the above class, which is positive in action and which will record characters and perform various auxiliary functions in a reliable and efficient manner.

For the accomplishment of the above objects, the invention contemplates the employment of a suitable distributing mechanism for distributing line current impulses to a suitable selecting mechanism, such as a group of magnets which in turn controls a translating mechanism. The translating mechanism preferably comprises a series of slidable plates having apertures or openings therein, each opening being provided with a loosely fitting spherical member or ball. The opening in the plates and the balls carried thereby are so arranged that for any given arrangement or permutation of the slidable plates, there will be one and only one set of balls in alignment with a selected member or there will be only one ball in each plate in alignment with a ball in each of the other plates and a selected member. This alignment of a given set of balls forms a fixed or rigid operating means for performing work. The positioning of the transmitting plates is determined or controlled by the selecting mechanism, but the power for moving the translating plates to their desired positions is supplied by a power shaft controlled by the distributing mechanism. The characters to be recorded are determined by the selecting mechanism and the positioning of the transmitting plates, while the force or power for actuating the recording mechanism is supplied by the power shaft.

The above and other objects of the invention will be fully understood from the following description and claims and by refer-

ence to the accompanying drawings, wherein Fig. 1 is a plan view of a portion of the receiving instrument with certain portions broken away to more clearly show some of the operating parts; Fig. 2 is a partial sectional view taken on the line 2, 2 Fig. 1; Fig. 3 is a sectional end view of the translating mechanism shown in Fig. 1; Fig. 4 is a side view of the translating mechanism shown in Fig. 1 and an end view of the power shaft and cooperating parts; Fig. 5 is a detailed view of a part of the cam shaft operating dogs carried thereby and cam sectors controlled by the operating dogs; Fig. 6 is a side elevation of a portion of one of the translator plates; Fig. 7 is a detailed view of an eccentric operated by the power shaft and a plurality of pull bars actuated thereby for performing various auxiliary functions, such as line feed, carriage return, shifting from upper case to lower case and vice versa, etc.; Fig. 8 shows a detail of the type carriage positioning means; and Fig. 9 is a diagrammatic skeleton view of the various operating and cooperating parts of the receiving instruments.

Referring to Fig. 9 for a bird's-eye view of the various operating and cooperating parts of the receiving instruments, 20 represents a receiving distributor for distributing the effects of line current impulses to a group of selecting magnets. The distributor 20 may be operated synchronously with another distributor at a distant station and may be maintained in synchronism by well-known means, or the distributor may consist of an intermittently operating distributor of the start-stop type which is released for the distribution of each group of character signals and arrested after the impulses have been distributed. This form of distributor is also well known in the art. The selecting magnets 21, 22, 23, 24 and 25 are double-acting magnets and the armatures and vanes 10 carried thereby are arranged to stay in whichever position they are last placed until a line impulse of opposite polarity is received. The vanes 10 are in the form of knives V-shaped members, better shown in Figs. 4 and 5, and cooperate with V-shaped rotatable dogs 12, carried by the power shaft 26. The operating dogs 12, while rigidly secured to the power shaft 26, for rotary movement have a certain amount

of lateral play and are adapted to be guided by the vanes 10 so that they pass on either side of their cooperating cam sector 14, which are pivotally supported at 57.

5 This invention, while not limited to any particular code, is shown in its preferred form as based on a five-unit code, such as the well-known Baudot code. Hence there are shown five selecting magnets each of which 10 controls a vane which cooperates with a particular operating dog carried by the rotatable shaft. There are also shown five cam sectors 14, cooperating with five irregular-shaped members 30, 31, 32, 33, and 34, which 15 are in the form of bell crank levers and pivoted at 35, 36, 37, 38 and 39 respectively. Each of the bell crank levers cooperates with a movable translator plate 41, 42, 43, 44 and 45. Each of the translator plates, 20 may be in either one of two positions. Each translator plate carries a plurality of spherical balls loosely placed in openings or apertures in the translator plates, and the arrangement of the balls is such that for any 25 given permutation or position of the five translator plates, one series or set of balls will be brought into alignment with a selected member and transversely of the translator plates. It will be seen that the 30 number of possible combinations or permutations of the translator balls is limited only by the number of plates, apertures and balls employed. In the preferred arrangement as disclosed in the accompanying 35 drawings, using five translator plates, there are provided thirty-two combinations. The translator is so arranged that whenever a series of balls is brought into alignment, one and only one of the selector members 46 will be actuated. Each of the 40 selector members 46 is coupled by a connecting link 47 to an individual striker bar 48. The number of striker bars 48 is equal to the number of type levers carried by 45 the type carriage plus a number of similar striker bars, depending upon the number of stunt operations or auxiliary functions to be performed.

A motor 49 is provided with a driving 50 gear 50, cooperating with a driven gear 51, for controlling the power shaft 26 through the friction clutch 52. The friction clutch may be of any suitable type, such, for example, as disclosed in copending application Serial No. 397,903, filed July 21, 1920. The power shaft 26 is normally under tension tending to rotate and is held from rotating by means of a stop arm 53 engaging the cam 54 and controlled by the release 55 magnet 55, which is included in a circuit connected to one of the distributor segments and arranged to be operated preferably after each group of selecting impulses has been received and distributed to the five selecting 60 magnets.

Referring now more particularly to Figs. 1, 4 and 5, the selecting magnets 21 to 25 inclusive, will be actuated in various combinations, depending upon the character to be recorded. The particular combination to be recorded will be set up on the selecting magnets, and the V-shaped vanes 10 carried thereby will be positioned to determine the path of travel of the operating dogs 12 before the cam shaft is released. As soon as the cam shaft is released by the energization of the release magnet 55, the operating dogs 12 will make a complete cycle and in so doing, will shift those of the cam sectors 14 which enter into the new combination 70 and in a different manner than in the last preceding character combination. The cam sectors 14 are pivotally supported individually, as shown at 56 and 57 (Figs. 4 and 5). The rear of each cam sector is provided with 75 an extension member. These members are indicated by reference characters 58, 59, 60, 61 and 62. The extension members 58 to 62 inclusive cooperate with the ends of bell crank levers 30 to 34 respectively. Thus 80 it will be seen that when the cam sectors 14 are actuated about their pivotal bearings 56 and 57, the bell crank levers 34 will be selectively operated and will be turned in either a clockwise or counter-clockwise direction about their pivotal bearings 35 to 39 85 inclusive, to thereby selectively actuate the translating plates 41 to 45 inclusive. The translator plates 41-45, and the spherical balls 63 carried thereby are adapted to slide or reciprocate in a case or container 64. The container is preferably arranged so that it may be filled with oil or vaseline, if desired, to eliminate wear and friction between the translator plates and the balls carried 90 thereby.

The translator plates, in addition to carrying the spherical balls 63, are also provided with rectangular openings or apertures 65, and associated with each of the apertures 65 is a mortise or partial indentation 66, (Fig. 6). Passing through each of the apertures 65 and adapted to reciprocate therein, is a member 67 connected to an actuating arm 68, pivotally supported at 69. Each of the members 67 is provided on the lower edge thereof with a series of extensions equal to the number of translator plates, and the extensions are adapted to cooperate with the indentations 66 in the translator plates for the purpose of positively restoring the selected members to normal position simultaneously with the selection of a succeeding member. To each of the operating members 68 is pivotally connected a lug or plunger 70, extending through an opening in the side of the translator case 64. The inner end of the plunger 70 is rounded or spherical and is adapted to cooperate with or be actuated by the 100

translator balls 63. On the opposite side of the translator case 64 and in alignment with each set or combination of translator balls, is a semi-spherical member 71, which 5 is keyed or rigidly secured to the translator case, as shown in Fig. 3. It will be noted that the plungers 70 and members 67 are connected to the actuating members 68 on opposite sides of their pivotal bearings 69. Thus, whenever a series of balls, carried by the translator plates, is brought into alignment with a plunger 70, as shown in Fig. 3, one of the plungers, as indicated at 70°, will be forced outwardly and the 10 corresponding member 67^a connected to the extremity of actuating member 68^a will be moved into the position shown, and when in this position, the downwardly extending lugs carried by the member 67^a will be 15 forced into the indentations 66 of the translator plates. Then when a succeeding selection is set up by a rearrangement of the translator plates the member 67^a will be returned to its normal position and likewise 20 the other operating elements connected thereto. The number of actuating members 68 is equal to the number of type bars to be actuated plus the number of auxiliary functions to be performed, such as line feed, 25 carriage return, etc. Each actuating member 68 is connected to an individual striker bar 72 by means of a connecting link 73. The striker bars 72 are carried or supported by a pair of stationary rack members 74 30 and 75. Adjacent the fixed rack member 74 is a reciprocating rack member 76, and adjacent the fixed rack member 75 is another reciprocating rack member 77. These 35 two reciprocating rack members are interconnected by shafts or rods 78 and 79 and corresponding bell crank levers 80 and 81 in the form of a parallelogram, so that the two reciprocating racks receive parallel motion. Bell crank levers 80 and 81 are pivoted to rods 78 and 79, respectively. The 40 striker bars 72 are provided near each end, with a downwardly extending lug or member 82. These lugs are normally out of the path of reciprocation of the rack members 45 76 and 77, but when moved by the translator into a selected position, the lugs are moved into the path of the reciprocating rack members. Mounted just above and 50 adapted to cooperate with each of the character striker bars 72 is an actuating member 83, pivoted at 84 near its center and connected at one end with a pull bar 85, which is in turn connected to a corresponding type lever 86. Each of the actuating members 83 is provided at its forward end with a downwardly extending lug or member which is adapted to be engaged by its corresponding striker bar 72. The 55 actuation of the striker bar 72 thus imposes motion to its corresponding type lever 60 65 86, thereby causing it to impress or print a character in a manner well understood in the art. The power or means for actuating the reciprocating rack members 76 and 77 is supplied from the power shaft 26, on which is mounted an eccentric 87. After the selecting dogs 12 have been positioned, the power shaft 26 is released operating the translating mechanism which translates into the position of selecting dogs 12 a mechanical movement by placing or positioning one of the striker bars 72 in the path of motion of the rack members 76 and 77. The continued rotation of the power shaft 26 in the direction of the arrow, and by 70 means of the eccentric 87, connecting links 88 and 89, and rocker arms 90 and 91, the racks 76 and 77 are reciprocated, as clearly shown in Fig. 2. The moment the selecting element individual the striker bar 83 is moved so that the projections 82 are in the path of the racks 76 and 77, the desired character will be printed owing to the positive action produced through the movement of these racks. 75 80 85 90

The rocker arm 90 is pivotally connected at 92 to a block 93, adapted to be positioned in a boxing or housing as shown in Fig. 2. The knurled knob 94 and threaded member 95 cooperates with the block 93 for the purpose of varying the position of the block and consequently the effectiveness of the type blow against the platen. 95

The type carriage, including the type levers 86, pull bars 85, actuating members 83 and frame on which they are mounted, are adapted to be moved transversely of the striker bars 72, translating and power mechanism, in a manner as disclosed and claimed in copending application Serial No. 173,546, filed June 8, 1917, Patent No. 1,374,603, granted April 14, 1921. 100

In Fig. 7 is shown an eccentric 96 for operating an auxiliary striker bar 97. The auxiliary striker bar is adapted to engage a selected one of a plurality of auxiliary function pull bars 98, 99, 100 and 101 when selected. The pull bars 99 to 101 inclusive 105 may be employed to effect such operations as line feed, carriage return, shift and unshift, or any other auxiliary functions as may be required. The auxiliary function pull bars are normally out of the path of the reciprocating striker bar 97, but are adapted to be selectively drawn into the 110 path of the striker bar 97 by the connecting links 102 and bell crank levers 103 which are arranged to cooperate with and be actuated by auxiliary striker bars 104, which are actuated and controlled in the same 115 manner and by the same mechanism as the character striker bars 72. Complete details of the actuating mechanism controlled by the auxiliary function pull bars and the 120 manner in which they may be utilized in a 125 130

practical installation, is fully disclosed and described in Patent No. 1,374,606, April 12, 1921, and since these features are claimed in this patent and form no part of the present invention, a further description is unnecessary.

The type carriage 105 is supported by track or rail members 106 and 107 over which wheels are arranged to travel. The type carriage 105 is preferably so arranged as to be practically balanced on the rail 106. Rigidly secured to the front of the type carriage 105 is a wheel or roller 108 arranged to travel on the underneath edge of the rail 107. On the upper part of the rail 107 and adapted to travel thereon, is a second wheel 109 carried by a link member 110, rigidly secured to the frame of the machine at 111. The free end of the link 110 to which the wheel 109 is attached, is connected by means of a spring 112 to an extension of the bearing of wheel 108. This arrangement tends to hold the type carriage in place and prevents binding between the stationary and movable parts.

It will be understood from an examination of the drawings and a comparison of Fig. 9 with other figures of the drawings, such as Figs. 1, 2 and 3, that Fig. 9 shows one form in which the invention might be practiced, although a preferred form for operating the translator plates and imparting mechanical movements to members controlled thereby, as well as the actuation of the striker bars, is illustrated in the remaining figures.

For a further disclosure of any features not illustrated or claimed in this application, reference may be made to copending application Serial No. 397,903 filed July 21, 1920, and Patent No. 1,374,606, April 12, 1921.

What is claimed is:

1. In a printing telegraph receiver, the combination of a selecting mechanism responsive to line current impulses, a controlling mechanism controlled thereby comprising a plurality of movable members adapted to be arranged in various combinations, a plurality of independently movable selectable elements, and work members actuated solely by energy imparted thereto by the movement of said movable members for selecting one of said independently movable elements for operation.

2. In a printing telegraph receiver, the combination of a selecting mechanism responsive to line current impulses, a translating mechanism comprising translating plates, elements carried by said plates, power operated means controlled by said selecting mechanism for positioning said elements, a plurality of independently movable selectable elements and work members actuated

by said elements for conditioning one of said selectable elements for operation.

3. In a printing telegraph receiver, a selecting mechanism, a plurality of independently movable type elements, a translating mechanism comprising a plurality of members movable in various combinations, means forming a part of said selecting mechanism for moving said members, and means actuated by the movement of said members for directly selecting one of said type elements for operation.

4. In a printing telegraph receiver comprising distributing, selecting, translating, and recording mechanisms; said translating mechanism comprising a plurality of movable members; elements carried by said movable members and adapted to be arranged to form a rigid mechanical operating means one with another; and means actuated by said elements to control the printing of characters.

5. In a printing telegraph receiver, a power shaft, a plurality of operating members carried thereby, a plurality of members associated therewith and adapted to be moved in either one of two directions by said operating members, a series of translator plates controlled thereby, and work members adapted to be selectively actuated in various combinations directly upon the movement of the translator plates.

6. In a printing telegraph receiver, a translating mechanism comprising a series of translating members, apertures in each of said members, elements carried loosely in each of said apertures and adapted to be aligned one with another to form a rigid mechanical member, and a work member operated by the pre-determined alignment of said translator elements.

7. In a printing telegraph receiver, a translating mechanism comprising a plurality of translator plates, a plurality of elements carried by each of said plates, means controlled by line current impulses for determining the position of said plates, power operated means for moving said plates as determined by said means to bring one element carried by each plate into alignment with a corresponding element of each of the other plates to form a rigid mechanical operating member, and a work member operated solely due to the alignment of said elements.

8. In a printing telegraph receiver, a translating mechanism comprising a series of translator plates, means controlled by line current impulses for selectively actuating said plates, apertures in said plates, one of said apertures in each of said plates arranged to be brought into alignment with a corresponding aperture in each of the other of said plates, a spherical member carried in

each of said apertures, an all mechanical member operated directly due to the alignment of said spherical members, and printing mechanism controlled by said last-mentioned member.

9. In a printing telegraph receiver, a plurality of selecting magnets, a translating mechanism comprising a series of translator plates, power operated means for positioning said translator plates to a selecting position as determined by said selecting magnets, a single selector element of a plurality of said elements adapted to be moved to a predetermined position by said translator mechanism, and means for positively restoring said single selected selector element by a subsequent movement of said translator mechanism.

10. In a printing telegraph receiver, a plurality of selecting magnets responsive to line current impulses, a translator mechanism comprising a plurality of translator plates adapted to be arranged in varying permutations, power operated means controlled by said magnets for positioning said translator plates as determined by the combinations set up on said selecting magnets, a single selector element of a plurality thereof responsive to a predetermined arrangement of said translator plates, and means for positively restoring the single selected selector element to normal simultaneously with the actuation of a second selector element as determined by the re-arrangement of said translator plates.

11. In a printing telegraph receiver, a plurality of selecting magnets, a power shaft, a plurality of rotatable members carried by said power shaft, a corresponding number of cam sectors separately mounted from said rotatable members and associated therewith and adapted to be actuated by the movement thereof, a translating mechanism actuated by the movement of said cam sectors, and a recording mechanism controlled by the translator mechanism.

12. In a printing telegraph receiver, a plurality of selecting magnets, a rotatable shaft, rotatable operating members carried by said shaft, said operating members having two paths of travel, a cam sector associated with each of said operating members and actuated thereby, a translating mechanism comprising a translator plate individual to each of said cam sectors, elements carried by each of said translator plates and arranged upon the movement thereof to be aligned to form a rigid mechanical operating member, and work members actuated due to the formation of such mechanical operating connection.

13. In combination, a plurality of perforated plates, elements arranged in said perforations and brought into alignment one with another by moving said plates in pre-

determined combinations, electromagnetic means for determining the positions of said plates, power mechanism independent of said electromagnetic means for moving said plates in accordance with the energization of 70 said electromagnetic means, and members actuated mechanically by said elements when moved into alignment.

14. In combination, a rotatable power shaft, a plurality of members attached 75 thereto, each of said members having a plurality of paths of travel, electromagnetic means for determining the path to be traversed by each member, a plurality of operating elements controlled thereby, each of 80 which is adapted to be moved into either of two positions simultaneously with the movement of its respective member, and work members actuated by the movement of said elements.

15. In combination, a power shaft, a series of operating dogs carried thereby, each of said dogs having two paths of travel, electromagnetic means for determining the path to be traversed by each dog, an operating 90 element controlled by each dog and moved into either of two positions simultaneously with the movement of its respective dog, and work members actuated by the movement of said operating elements.

16. In combination, a power shaft normally tending to rotate, operating dogs carried thereby, each of which has two paths of travel, electromagnetic means for determining the path of travel of each dog, a plurality of members having openings therein, balls in said openings, operating means attached to said members and controlled by said dogs whereby said balls are brought into alignment one with another to form a rigid operating means, and work members actuated by the alignment of said balls.

17. A series of parallel members, each of which is adapted to occupy either of two positions, openings in said members arranged in predetermined combinations, spherical members carried in said openings, electromagnetic means controlling the movement of said parallel members whereby said spherical members are brought into alignment one with another to form a rigid mechanical operating means, all-mechanical means for holding said parallel members in their actuated positions, and all mechanical work members actuated by the alignment of 115 said spherical members.

18. In combination, a series of plates having openings therethrough arranged in predetermined combinations, power means for moving said plates in either of two positions, elements arranged in the openings in said plates and brought into alignment one with another by the movement of said plates, work members actuated by the alignment of 120 said elements, and means controlled by 130

the subsequent movement of said plates for restoring said work members.

19. In combination, a series of plates having openings therein arranged in predetermined combinations, electromagnetic means for controlling the movement of said plates, a rotary power shaft for moving said plates in either of two positions as determined by said electromagnetic means, elements carried in the openings of said plates and brought into alignment one with another when said plates are selectively arranged in predetermined combinations, work members actuated by the alignment of said elements, and means responsive to the movement of one or more of said plates for restoring said work members to normal. ¹⁵
- 10 In witness whereof, I hereunto subscribe my name this 12th day of November A. D., 1920.

MERLE P. CHAPLIN.
